BRAKE MECHANISM FOR TALKING MACHINES.

1,406,579.

Specification of Letters Patent. Patented Feb. 14, 1922.

Application filed August 16, 1919. Serial No. 317,883.

To all whom it may concern:

Be it known that I, MARTIN NYSTROM, a citizen of the United States, residing at Chicago, in the county of Cook and State of Illinois, have invented certain new and useful Improvements in Brake Mechanisms for Talking Machines, of which the following is a specification.

The object of this invention is to provide 10 a simple and effective brake mechanism for talking machines which can be easily operated by hand to quickly start or stop the motor and which can be adjusted to automatically and quickly stop the motor at a predetermined point in the operation of the machine.

Further objects and advantages of my invention will be pointed out hereafter in 20 the detail description of a preferred embodiment thereof as illustrated in the accompanying drawings, in which—

Fig. 1 is a perspective view, partly broken away and in section, illustrating my invention applied to a talking machine motor;

Fig. 2 is a top plan view;

Figs. 3 and 4 are detail views.

Referring to the drawings, 5 is the frame of a talking machine motor provided with a spindle 6 which projects up through the 30 top plate or motor board 7 to receive and carry the record table (not shown). Such a motor is customarily supplied with means for regulating the speed of rotation of the spindle which include a governor designated 35 generally 8 and comprising the drum 9. Devices (not shown) adapted to be adjusted to position by turning the pin 10 are arranged to engage the drum as the latter moves longitudinally of the governor shaft 40 11 and thus control the speed of rotation of the spindle. This governor mechanism forms the subject-matter of a companion application Serial No. 317,882, filed August 16, 1919.

A plate 12 is fastened on the top plate or motor board 7 and is provided at one end with a guide finger 13. A spindle 14 is rotatably mounted on the plate 12 and projects down through an opening provided for it in 50 the top plate or motor board 7. This spindle carries a block 15 provided with a pin 16 which is engaged by the forked end 17 of a brake lever 18 rotatably supported in the motor frame 5. The brake lever is 55 provided with an arm 19 carrying a pad 20

which is arranged to engage the periphery of the drum 9. A latch lever 21 is rigidly mounted on the spindle 14 above the top plate or motor board 7 and it is provided adjacent the periphery with an operating 60 notch 22 and a locking shoulder 23. The stop lever of the brake mechanism consists of a front section 24 pivoted to the plate 12 at 25, and a rear section 26 pivoted at 27 to the front section 24 at the rear end of the 65 latter, back of the pivot 25. The pivot 27 holds the front end of the lever section 26 in close frictional engagement with the rear end of the front lever section 24 so that the rear section may be adjusted independently of the front section by operating the handle 26' to set the brake for action at a particular point in the operation of the machine, and yet the two sections will operate in unison as if rigidly connected together when 70 the latch lever is moved to start the motor and when the stop lever is moved to stop the motor. There is a downward projection 28 at the forward end of the front section 24 of the stop lever which engages the notch 22 75 while the motor is running and which engages the shoulder 23 when the motor is not running. A pin 29 carried by the tone arm (not shown) of the talking machine is arranged to engage the rear end of the rear 80 section 26 of the stop lever to swing this lever on its pivot 25 and shift the projection 28 from the notch 22 to position against the shoulder 23. A spring 30 is fastened to a lug 31 on the front section 24 of the stop 85 lever and to a lug 32 on the latch lever 21, the said lugs being positioned with relation to each other so that in the two positions of said levers the spring will lie on the same side of the axis of the spindle 14. 90

The front section 24, which constitutes the locking lever, has a limited range of movement sufficient only to engage the lug 28 with notch 22 and this lever is limited in its movement by a lug 12' on the plate 12. The 100 rear section 26 of the lever, which constitutes a setting lever, has a wide range of adjustment independent of the locking lever so that the mechanism may be adjusted to stop the machine at any time within wide 105 limits of adjustment without in any way affecting the operation of the locking lever or the latch, it being apparent that the locking lever and latch always operate within certain fixed limits while the setting lever is 110

capable of adjustment within any limits that may be required.

When the setting lever has been set to stop the machine at a predetermined point, by operating the handle 26', and the record being in place, the latch lever 21 is thrown to the position shown in Fig. 3, thereby releasing the pad from engagement with the drum and permitting the motor to operate. At 10 this time the locking lever lug 28 is seated in the notch 22 of the latch lever to hold the brake pad out of engagement with the drum so that the motor may freely operate. When the tone arm has moved to engage the pin 15 29 with the setting lever 26 the latter, operating with the locking lever, as one complete releasing lever, is shifted on the pivot 25 to withdraw lug 28 from notch 22, whereupon spring 30 pulls the latch lever around 20 to the position shown in Fig. 4 with the end of the locking lever 24 in engagement with the shoulder 23. Thus the swinging movement of the latch lever is limited by engagement with the locking lever and its movement is sufficient to rock the brake rod 18 25 and carry the brake pad into operative engagement with the drum and stop the motor.

My improved mechanism is simple but efficient in construction and operation. It permits the brake to be set for operation at any point on records of all known sizes and it permits this to be done in a simple manner without necessitating any adjustment of the locking parts.

I am aware that changes in the form and proportion of parts and in the details of construction may be made without departing from the spirit or sacrificing any of the advantages of the invention and I therefore 30 reserve the right to make all such changes as fairly fall within the scope of the following 40 claims.

I claim:

1. In a brake mechanism for talking machines, the combination of a latch lever, braking means connected with and operated by said latch lever for stopping the motor of the machine, a locking lever pivoted adjacent its rear end and adapted to engage at its forward end with the latch lever to temporarily lock the parts with the brake in operative position, a setting lever pivoted at its forward end to the rear end of the locking lever behind the locking lever pivot, the rear end of said setting lever being arranged in the path of a moving part of the machine and actuated thereby, said locking lever and setting lever being frictionally engaged for independent adjustment 50 of the setting lever and for conjoint movement to release the latch and to hold the brake in inoperative position.

2. In a brake mechanism for talking machines, the combination of a latch lever, a

pivoted locking lever adapted to engage at 65 its forward end with the latch lever to temporarily lock the parts with the brake in operative position, a setting lever pivoted to the locking lever and arranged in the path of a moving part of the machine and actuated 70 thereby, said locking lever and setting lever being frictionally engaged for independent adjustment of the setting lever and for conjoint movement to release the latch and to hold the brake in inoperative position, a 75 spindle operated by said latch lever, a governor mechanism on the motor comprising a drum, a brake pad arranged to engage the drum to stop the motor, and means operated by said spindle for moving said pad to and 80 from engagement with said drum.

3. The combination with the governor of a talking machine motor, said governor comprising a drum, of a brake pad adapted to engage said drum to stop the motor, an arm 85 carrying said pad, a revolute rod carrying said arm and having a forked end, a spindle, a block on said spindle, a pin on the block operatively engaged with the forked end of said brake rod, and means for operating said 90 spindle to set or release the brake.

4. The combination with the governor of a talking machine motor, said governor comprising a drum, of a brake pad adapted to engage said drum to stop the motor, an arm 95 carrying said pad, a rod carrying said arm and having a forked end, a spindle, a block on said spindle, a pin on the block operatively engaged with the forked end of said 100 brake rod, a latch lever rigid with said spindle, a locking lever engaged with said latch lever to hold the latch lever with the brake in set or release position, and an adjusting lever arranged in the path of a moving part of the machine to be actuated thereby and 105 connected with the locking lever for independent operation or for conjoint operation with the locking lever.

5. The combination with a talking machine motor, of braking means therefor, a 110 spindle adapted to rock and actuate said braking means, a latch lever rigidly mounted on said spindle, a locking lever to engage said latch lever when said spindle is in brake release position, a spring connecting the 115 latch lever and the locking lever and held at tension when the locking lever is in locking engagement with the latch lever, and an adjustable lever disposed in the path of a moving part of the machine to be actuated thereby for disengaging the locking lever from the latch lever and permitting the spring to swing the latch lever and rock the spindle 120 for applying the brake.
